COMBINATION HEATING AND COOKING RANGE

Joseph E. Leonard, Berkeley, Calif., assignor to
Hammer-Bray Company, Ltd., Oakland, Calif.,
a corporation of Nevada

Application January 21, 1936, Serial No. 60,013

3 Claims. (Cl. 126—4)

The invention relates to household stoves or ranges which have built in as a part thereof a gas-operated air-circulating heater usually located at one end of the stove.

5 An object of the invention is to incorporate in the range a heater unit of the character described which will not only provide for efficient heating of the air, but will insure ready and free exit of all the air heated in the unit and a minimum loss of heat by conduction through the contiguous stove parts.

Another object of the invention is to provide 10 a heater and fire box combination for the range in which the relative positioning and arrangement of the heater and fire-box parts are such that the heat from the fire-box may radiate directly through the same opening which affords the exit of the hot air from the heater.

A further object of the invention is to provide 15 a heater and fire-box combination in which the heated products from the chamber are vented to the fire-box in a manner insuring a maximum utilization of the heat resident in the vented products, both for heating the air in the heater and for radiation of heat from the heater.

The invention possesses other objects and features of advantage, some of which, with the foregoing, will be set forth in the following description of the preferred form of the invention which 20 is illustrated in the drawing accompanying and forming part of the specification. It is to be understood, however, that variations in the showing made by the said drawing and description may be adopted within the scope of the invention 25 as set forth in the claims.

Referring to said drawing:

Figure 1 is a perspective view of a range embodying the heater and fire-box arrangement of my invention.

40 Figure 2 is an enlarged vertical sectional view of the heater and fire-box portion of the range, the plane of the section being indicated by the line 2—2 of Figure 1.

Figure 3 is a horizontal sectional view taken on 45 the line 3—3 of Figure 2.

Figures 4 and 5 are views similar to Figure 2, but showing modified forms of the invention.

As illustrated in the first referred to embodiment of the invention, the heater and fire-box arrangement and design are incorporated in a range 2 of the type known as the table-top, that is in which all of the stove parts are usually located below the cooking top 3 and such top is arranged to be covered by a removable plate or cover 4. In the range shown, the heater, which

is designated by the numeral 6, and the fire-box 7, are positioned at one end of the range, while oven and boiler compartments 8 and 9 are disposed in superposed relation at the other end of the range. The fire-box is located inwardly of the heater and adjoins, at the end opposite the heater, a top gas burner chamber 12 and a set of warming compartments 13 and 14 arranged one under the other and both under the chamber 12, the compartments being desirably provided with 10 drawers 16 whose front walls 17 form a closure for the compartments and a portion of the front wall of the stove. It will be seen by reference to Figure 2 that the portion of the range comprising the heater and fire-box is of the same vertical 15 dimension as the oven and broiler portion and as the portion made up of the compartments and burner chamber; in other words the heater and box portion extend from the cooking top down to the bottom frame member 18 of the range. 20 In the case of the heater, the lower extremity of the combustion chamber casing 19 and the burner 21 therefor are located at the immediate bottom of the range, that is, at the member 18, and thus the heating of the air for circulation is initiated 25 close to the floor, and, particularly where the stove legs 22 are short, the air near the floor of the room will be kept substantially as warm as the air at the more elevated levels therein.

As will be clear from Figure 2, the fire-box, 30 which includes the box proper and the ash pit, is preferably coextensive vertically with the heater unit and is contained within a casing 23 whose side wall 24 is spaced from the end wall 25 to provide the heater compartment. The combustion chamber casing 19 of the heater, as previously explained, has its lower extremity at the member 18 and extends upwardly preferably to a point about even with or below the grate 26 of the box. The casing 19 desirably extends for 40 almost the full distance of the stove from the front to the rear side thereof, but is relatively narrow in width with the sides of the casing converging upwardly and spaced from the wall 25 and the casing 23 so as to define vertical passages 45 28 and 29 for the flow of the warmed air during the operation of the heater. It will be evident that since the casing 19 terminates considerably below the top of the stove, a large space or chamber 31 will be formed between said top and the casing in which the heated air from the passages 28 and 29 may discharge, and in order to permit the ready exit of such air from said space 31, preferably the entire portion of the end wall 25 lying opposite said space is left open and formed 50 55

to provide a grilled discharge opening 32 which as here shown is extended downwardly well below the top of casing 19. In view of the large dimensions and positioning of the hot air delivery chamber 31 and of the hot air discharge opening 32, notwithstanding the interposition of the passage 29 between the opening 32 and passage 28, the smooth and ready flow of the air from the passage 28, as well as from the passage 29, is assured and no trapping of the hot air within the heater and the resultant loss of heat through conduction to the contiguous stove parts may occur. In order to increase the size of the fire box, particularly at the upper portion thereof, the side wall of the box, which adjoins the chamber 31, is offset in the direction of such chamber, and such offset, in addition to affording the enlargement of the box, serves to more effectively guide the heated air, especially from the passage 28, to the discharge opening 32.

As an effective means of venting the products in the combustion chamber 19, a vent pipe 34 connects the top of the chamber directly with the fire box, and such pipe extends through the delivery space 31 and incidentally provides for the additional heating of the air in such space. The vented products, after passing into the fire box, are arranged to discharge therefrom through a controlled flue opening 36 in the rear wall of the box, and in order to prevent any ashes or other particles from falling into the vent pipe a shield 37 is positioned over the vent opening in the box.

It will be understood that a circulation of air will be induced through the passage 28 and the delivery chamber 31, independent of the operation of the heater, when the fire-box is being utilized for burning trash or other fuel of one kind or another, and it is important to note that by reason of the fact that the fire box is immediately opposite the opening 32 and practically no portion of the heater casing or other obstruction is interposed between the box proper and such opening, the heat generated in the box may radiate directly through said opening. Likewise the heat from the vent pipe 34 may also radiate through the opening. Desirably the vent pipe connects with the forward end of the fire-box so that the vented products are forced to traverse the full length of the box before being allowed to escape through the flue opening 36 at the rear end of the box. With this arrangement as contrasted with one when the pipe connects with the fire box at the middle or rear thereof, more heat will be extracted from the vented products before the latter may escape from the stove and at the same time the wall of the fire box adjoining the delivery chamber 31 will serve more effectively to transmit the heat back to such chamber. The front of the portion of the range comprising the fire-box and heater is here shown closed by a door 38, and preferably the front and rear walls of the heater casing 19 are spaced inwardly from the corresponding walls of the stove so as

to provide additional air heating passages therat.

In the embodiment of the invention illustrated in Figure 4, the entire side wall 41 of the fire box proper adjoining the heater chamber is offset so as to afford a relatively large capacity box and yet leave the chamber well able to efficiently handle the hot air admitted thereto.

A somewhat more pronounced change is depicted in Figure 5. In this embodiment the combustion chamber casing 42 of the heater is located practically entirely under the fire-box, but the event pipe 43 of the casing still extends upwardly through the hot air delivery space 31.

I claim:

1. In a cooking and heating stove having an incinerator and an air circulating heater embodied therein, a stove body having a pair of compartments in side by side relation, an incinerator in one of said compartments and providing a fire box in the top of said compartment and an ash pit under said fire box, said compartments being narrowed at said ash pit with a corresponding widening of said other compartment therat, and a combustion chamber casing mounted in the widened portion of said last named compartment and being spaced from the sides of said compartment to define an air heating and circulating passage.

2. In a cooking and heating stove having an incinerator and an air circulating heater embodied therein, a stove body having a pair of compartments in side by side relation and extending from substantially the rear to the front of said body, an incinerator in one of said compartments and providing a fire box in the top of said compartment and an ash pit under said fire box, said compartment being narrowed over a major portion of its depth at said ash pit with a corresponding widening of said other compartment therat, a combustion chamber casing mounted in the widened portion of said last named compartment and being spaced from the sides of said compartment to define an air heating and circulating passage, a burner for heating said casing, and means for discharging air in said passage from said body.

3. In a cooking and heating stove having an incinerator and air circulating heater embodied therein, a stove body having a pair of compartments in side by side relation with a common partition wall, an incinerator in one of said compartments and providing a fire box at the top of said compartment and an ash pit under said fire box, said partition wall having an obliquely sloped portion below said fire box and effective to narrow said last named compartment at said ash pit and correspondingly widen the said other compartment, and a combustion chamber casing mounted in said last named compartment at the widened portion thereof and being spaced from the sides of said compartment to define an air circulating and heating passage.

JOSEPH E. LEONARD.
